[57] CLAIM

The ornamental design for a beverage container holder, as shown and described.

DESCRIPTION

Fig. 1 is a front elevation view of the beverage container holder showing my new design;

FIG. 2 is a rear view thereof;

FIG. 3 is a top view thereof;

FIG. 4 is a left side view thereof;

FIG. 5 is a right side view thereof; and,

FIG. 6 is a bottom view thereof.

The broken lines showing the bottle in FIG. 1,2,4 and 5 are for illustration purposes only and forms no part of the claimed design.
